UNITED STATES PATENT OFFICE.

WILLIAM P. HARTSOCK, OF DAYTON, OHIO.

DESIGN FOR AN ADVERTISING DEVICE.

Application filed April 28, 1922. Serial No. 2,010. Term of patent 14 years.

To all whom it may concern:

Be it known that I, WILLIAM P. HARTSOCK, a citizen of the United States, residing in the city of Dayton, county of Montgomery, and State of Ohio, have invented a new, original, and ornamental Design for an Advertising Device, of which the following is a specification, reference being had to the accompanying drawing, forming part hereof.

The figure is a perspective view of an advertising device, showing my new design.

I claim:

The ornamental design for an advertising device, as shown.

WILLIAM P. HARTSOCK.

Witness:

HOWARD S. SMITH.
